AUTOMOBILE REAR VIEW MIRROR

Robert Grove, Birmingham, Mich., assignor to Chrysler Corporation, Highland Park, Mich., a corporation of Delaware

Filed June 17, 1959, Ser. No. 56,389

Term of patent 7 years

(Cl. D14—6)

Fig. 1 is a side elevational view of an automobile rear view mirror showing my new design;

Fig. 2 is a front elevational view thereof; and

Figs. 3, 4 and 5 are sectional views taken on the lines 3—3, 4—4 and 5—5, respectively, of Fig. 1.

The dominant features of my design reside in the portions shown in full lines.

I claim:

The ornamental design for an automobile rear view mirror, substantially as shown and described.
